ELECTROSTATIC DUST PRECIPITATOR

Edward H. R. Pegg, Cranford, N. J., assignor to
Westinghouse Electric Corporation, East Pitts-
burgh, Pa., a corporation of Pennsylvania

Application December 29, 1945, Serial No. 638,356

2 Claims. (Cl. 183—7)

1

My invention relates to electrical dust-precipitators for removing dust-particles from a flowing gas stream, by dust-particles meaning any foreign particulate matter carried by the gas, in accordance with the usual understanding of the term in this art.

A primary object of my invention is to provide an electrical dust-precipitator which can be easily assembled from cheap, readily constructed and interchangeable parts.

A further object of my invention is to provide a small compact electrical dust-precipitator for removing dust-particles from a flowing gas by first charging gas-borne dust-particles and then removing charged dust-particles from the gas stream. To this end, an upstream dust-charging means and a downstream dust-precipitating means are provided; the former consisting of longitudinal tubular members having axial ionizing wires, and the latter consisting of closely spaced alternatively relatively insulated and uninsulated plate-electrodes. In a form of my invention, the electrical dust-precipitator consists of two sections, in side-by-side relation. The dust-charging means is in the first of the sections and the dust-precipitating means in the second. Both can be slidably fitted into the sections.

Another object of my invention is to provide an ionizing means of a type utilizable in gas-cleaning, which can be readily constructed as a complete unit for sliding into an existing gas-duct of small cross-sectional area.

Objects, features, combinations and innovations of my invention, in addition to the foregoing, will be discernible or obtainable from the following more detailed description and accompanying drawing. In the drawing:

Figure 1 is a longitudinal sectional view, partly in elevation, of a gas-cleaning apparatus in accordance with my invention. The section is substantially along the line I—I of Fig. 2.

Fig. 2 is a sectional view substantially along the line II—II of Fig. 1.

Fig. 3 is a broadside view of an end-plate utilized in the foregoing form of my invention; and

Fig. 4 is a sectional view, with parts broken away, of a modified form of electrical dust-precipitator in accordance with my invention.

Referring more particularly to Figs. 1, 2 and 3, a gas-conduit 2 is provided which, in this particular instance, consists of a single pipe or tube member which is square in cross-section and provided with end flanges 4 for association with other parts of an air-conditioning means, if desired, or

2

other apparatus. Air or other gas is caused to flow through the gas-conduit in the directions of the arrows A at the left of Fig. 1. The gas flows longitudinally through the gas-conduit, by longitudinally meaning axially along a tubular member or in the direction of gas flow. The gas passes through a dust-charging means, indicated in its entirety by the reference numeral 6, and then through a dust-precipitating means, indicated in its entirety by the reference numeral 8.

The dust-charging means 6 and the dust-precipitating means 8 are so constructed as to be slidable into the gas-conduit 2, being retained by a friction fit, but obviously securing means 15 may be provided. If desired, a spacing bar 10 may be inserted between the dust-charging means and the dust-precipitating means for maintaining them a predetermined distance apart for adequate insulation between the high potential parts 20 of either with respect to the grounded parts of the other.

The dust-charging means 6 comprises a pair of end-plates 12 and 14, respectively. The end-plates are alike, within practical limitations, so that the description of one should suffice for both. The end-plate is of polygonal shape to correspond to the inside of the gas-conduit 2, which in this case is square. The end-plate has turned flanges 16 along each of its sides adapted to abut the gas-conduit. A small hole 18 is provided at the center of the end-plate and spaced about this hole are four circular openings 20; the centers of which lie on the corners of a square nested within the periphery of the end-plate.

The end-plates 12 and 14 are arranged with their flanges 16 directed toward each other and a tie-rod 22 is provided between them, having shoulders 24 at opposite ends for abuttingly receiving the end-plates. The outwardly extending parts 26 of the tie-rod are threaded to receive outwardly extending insulators 28 and 30. The insulator 28 clamps the end-plate 12 between it and a shoulder 24; and the insulator 30 clamps the end-plate 14 between it and the opposite shoulder 24. If the tie-rod is too thin, washers 45 may obviously be provided between the end-plate and shoulders for increasing the clamping area. The tie-rod 22 keeps the end-plates in parallel relation spaced apart a predetermined distance depending upon the length of the portion of the tie-rod between its shoulders 24.

It is evident that in the foregoing description I use the term "outer" and related words as referring to a direction away from a central point between the end-plates 12 and 14.

55 The end-plates are assembled so that their

openings 20 are longitudinally aligned. Disposed in each pair of aligned openings is a round tube 32 extending from one end-plate to the other. The tubes may be gas-tightly secured in the openings in any suitable manner, as for example, by sealing, welding or by sliding fit.

An armed member 34 is screwed to the outer insulated ends of each of the insulators 28 and 30 by means of screws 35 threaded into mating holes of the insulators. Each armed member 34 consists of a central portion from which a plurality of arms 36 project radially. These arms are thin so as not to cause too serious a disturbance in the flow of gas through the apparatus. The arms terminate at points longitudinally substantially in line with the axes of the tubular members 32 so that ionizing wires 38, which pass axially through the tubular members 32, may be anchored to the ends of longitudinally aligned arms 36. A clip or terminal 40 is provided on one of the arms 36 for receiving an insulated conductor for applying a high potential to the ionizing wires with respect to the tubular members 32.

The openings 20 and tubes 32 are laterally spaced apart in the embodiment shown, so as to provide sufficient metal centrally of the end-plates for receiving the insulators 28 and 30 without blocking off any significant part of the lateral area of the tubular members through which the gas flows. The end-plates are otherwise solid or gas-tight so that the gas is directed into the tubular members 32.

The dust-precipitating means 8 consists of any suitable spaced plate structure, but I prefer a construction along the lines of that shown in the Penney Patent No. 2,347,709, dated May 2, 1944, which discloses a precipitating unit adapted to slide into a gas-conduit. Preferably, it consists of a plurality of larger grounded plates 42 between which are disposed smaller insulated plates 44. A plurality of small interlocked insulating spacers 46 are provided between the plate-electrodes, and any suitable clamping means holds the assembly together.

Fig. 4 shows a unit of my invention in which the main gas-conduit consists of a plurality of sections 50, 52 and 54, formed by a full width partition 56 which terminates short of a removable bottom 58 so as to provide a path in which gas flows downwardly through the section 50, turns in the section 52, and flows upwardly through the section 54. The dust-charging means 6 is located in the section 50 and the dust-precipitating means 8 in the section 54.

While I have described my invention in preferred forms, it is obvious that it is subject to wide modification. For example, the contour of

the cross-section of the gas-conduit and of the tubular electrodes and corresponding openings may be of any desired shape and need not necessarily be rectangular or circular.

I claim as my invention:

1. A unitary structure of a type described comprising a pair of spaced end-plates having openings encompassed by the peripheries of the end-plates, parallel tubular members secured in said openings, a tie-rod between said tubular members parallel thereto, said tie-rod extending outwardly through said end-plates, said tie-rod having shoulders, insulators secured to the extended parts of said tie-rod, and clamping said end-plates between the insulators and said shoulders, arm members secured to outer ends of said insulators, and ionizing wires passing centrally through said tubular members, secured to said arm members.
2. An electrical dust-precipitator comprising, gas-conduit means providing a gas-flow path, having a pair of open-ended sections in juxtaposed relation and a common compartment spanning said sections, said gas-conduit means having a gas-inlet at an end of a first of said sections and a gas-outlet at the adjacent end of the second section, the other ends of said sections opening into said common compartment, said gas-conduit means comprising a removable outer closure means defining a wall of said compartment, a manually readily removable ionizing unit slidable into and out of said first section, and a manually readily removable dust-precipitating unit slidable into and out of said second section, each of said units being slidable into and out of the associated section through an opening covered by said removable closure means.
